(57) **CLAIM**

The ornamental design for a portable activity tray for children, as shown and described.

DESCRIPTION

FIG. 1 is a perspective view of a portable activity tray for children;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof;

FIG. 7 is a rear elevational view thereof; and,

FIG. 8 is a front perspective view of the portable activity tray of FIG. 1 showing the portable activity tray in an open position.

The broken lines shown are included for the purpose of illustrating portions of the portable activity tray for children that form no part of the claim.

1 Claim, 5 Drawing Sheets
